O. HODGKINSON.
WORK CLAMPING BENCH.
APPLICATION FILED SEPT. 9, 1921.

1,418,924.

Patented June 6, 1922.

UNITED STATES PATENT OFFICE.

OTRED HODGKINSON, OF OAKDALE, LOUISIANA, ASSIGNOR TO FRANK J. TRCKA, OF
NEW ORLEANS, LOUISIANA.

WORK-CLAMPING BENCH.

1,418,924.

Specification of Letters Patent. Patented June 6, 1922.

Application filed September 9, 1921. Serial No. 499,493.

To all whom it may concern:

Be it known that I, OTRED HODGKINSON, a citizen of the United States, residing at Oakdale, in the parish of Allen and State of Louisiana, have invented certain new and useful Improvements in Work-Clamping Benches, of which the following is a specification.

This invention relates to work clamping
benches and has particular reference to a
device of this general character especially
adapted and designed for use in setting up
and holding the framework of a rectangular
form, such as grain doors and the like, dur-
ing the construction of the same. Particularly
the present invention relates to an im-
provement on the device shown in the patent
to Frank J. Trcka, No. 1,245,638 issued Nov.
6, 1917.

20 An object of my invention is to provide a device of the above mentioned character having novel and improved clamping means whereby the boards or strips which enter into the construction of the door or other
25 rectangular form may be effectively held in assembled relation to facilitate the attachment of the battens or other reinforcing strips and which is capable of operation by a single operator or artisan.

30 A further object of my invention is to provide an improved movable clamping member extending longitudinally of the bench and overlying the upper surface thereof, movement of the clamping member being effected by operation of a longitudinally extending treadle operating a series of levers disposed at the opposite ends of a bench or table.

35

40 A further object of this invention is to provide a device of the above mentioned character which is simple in construction, inexpensive to manufacture, convenient in use, and strong and durable.

45 In the accompanying drawings wherein
for the purpose of illustration is shown a
preferred embodiment of my invention and
in which like numerals are employed to des-
ignate like parts throughout the several
views,

50 Fig. 1 is a perspective view of a bench or table provided with my improved clamping means and

Fig. 2 is an end view of the same.
Referring to the drawings, it will be noted

that I employ a work bench or table of any desired or preferred design and of such a construction as to give stability thereto and supported at its opposite ends by legs or standards 6. The front pair of legs or standards 6 project slightly above the plane 60 of the top surface of the table and are connected on their inner sides by a strip or bar 7 forming an abutment or guide for the side edges of the initial board or strip which enters into the construction of the door or other rectangular form. At one end of the table, I provide a second permanent abutment 8 to act as a guide for the marginal ends of the strips or boards. The remaining two sides of the table surface are unobstructed and flush, except for the improved clamping member to be hereinafter described. 70

Coacting with the working surface of the bench or table for the purpose of securely clamping the strips or boards in tight edge-wise relation, I provide along the rear edge of the table or bench, a longitudinally extending clamping bar or strip 9 capable of movement toward and from the adjacent edge of the table. This clamping bar 9 extends slightly above the plane of the working surface of the table when the same is in closed or clamping position and forces the strips or boards against the stationary abutment 7 at the opposite side of the table surface. Movement of this clamping bar 9 is effected by means of a series of levers disposed at opposite ends of the bench or table and comprising horizontally extending levers 10, to the upturned ends of which are rigidly secured the clamping bar 9. These levers 10 are disposed near the top of the table and are pivotally connected to the upper portion of the rear legs or standards 6 as shown at 11. Located below the levers 10 at a convenient height from the bottom of the table are the horizontally extending levers 12, pivotally connected to the lower portion of the rear legs or standards 6 as shown at 13, and extending slightly beyond the front legs or standards 6. The projecting ends of the levers 12 are connected by a suitable strip 14 forming a treadle for the operator's foot. A third pair of levers 15 are pivotally connected to the forward free ends of the levers 10 and extend downwardly to a connecting pivot 16 intermediate the ends of the levers 12. I further pro-

vide a pair of retractile coil spring members 17 the ends of which are secured to the rear standards 6 and to the levers 12 for the purpose of effecting an upward movement 5 of the levers 12 about their pivots 13. It is thus obvious that when pressure is brought to bear upon the treadle 14, that this downward movement is transmitted through the system or series of levers above described to 10 the clamping bar or strip 9 causing the same to move toward the adjacent edge of the bench or table. As soon as this pressure on the treadle 14 is removed, the retractile coil springs 17 return the clamping bar 9 to its 15 inoperative position.

In operation, the boards or strips which are to enter into the construction of the door or other rectangular form are assembled on the table surface edge to edge, the 20 initial board bearing edgewise against the longitudinal abutment 7, and the ends of the several boards abutting against the end stop 8. When the desired number of strips or boards have been assembled, the operator 25 places his foot upon the treadle 14 and exerts a downward pressure, overcoming the tension of the retractile coil springs 17 and causing the levers to act about their various pivots, thus forcing the inner face of the 30 clamping bar 9 against the outer edge of the nearest board or strip to securely press the boards or strips into intimate edgewise relation. While the boards are thus clamped, the operator applies the battens or other 35 reinforcing strips and nails the same and the several boards securely together. When this has been accomplished, the pressure is removed from the treadle 14 and the retractile coil springs 17 cause the clamping bar 9 40 to automatically move away from the adjacent edge of the bench or table and the as-

sembled door or other rectangular form may be readily and quickly removed.

It is to be understood that the form of my invention herewith shown and described 45 is to be taken as a preferred example of the same and that various changes in the shape, size and arrangement of parts may be resorted to without departing from the spirit of the invention or the scope of the sub- 50 joined claims.

Having thus described my invention, what I claim as new and desire to secure by Letters Patent is:—

A device of the character described comprising a work assembling table having a top surface and supporting legs at each corner of the same, a stationary abutment along the front edge of the top surface, a movable abutment at the opposite edge, an arm pivotally mounted upon each rear leg and at the upper portion of the same, said arms carrying at their rear end the said movable abutment, the said arms extending forwardly from their pivots to the front of the table, 60 a second arm pivotally mounted upon the lower portion of each of said rear legs, said second arms extending to the front of the table and substantially parallel with the first named arms, a third arm connecting 70 the forward end of each of the first named arms with the second named arms at a point midway of the length of the latter, a spring attached at one end to one of the rear legs and at its other end to one of the second 75 named arms, and a foot pedal connecting the forward ends of each of the second named arms and extending across the front of the table.

In testimony whereof I hereunto affix my 80 signature.

OTRED HODGKINSON.
